MULTISTAGE PROPELLER FAN

Harold F. Hagen, Wellesley, Mass., assignor to
B. F. Sturtevant Company, Boston, Mass.

Application January 26, 1942, Serial No. 428,211

8 Claims. (Cl. 230—122)

This invention relates to propeller fans and has as its object the elimination of fluctuations of pressure and volume caused by flow separation.

This application is a continuation-in-part of my copending application, Serial No. 365,596, filed November 14, 1940.

The fluctuations of pressure and volume caused by flow separation are very objectionable and are overcome in this invention by providing in a multi-stage propeller fan, propeller wheels which are so designed and proportioned with respect to each other and to the overall performance desired, that the stalling point for the blades of one wheel occurs at a different point from that of another, and that the overall characteristic curve is free from the dip or dips symbolical of flow separation.

In a preferred embodiment of the invention as embodied in a two stage propeller fan, the propeller wheel of the first stage handles substantially 60% of the work and the propeller wheel of the second stage handles substantially 40% of the work. By way of example in a two stage propeller fan providing 40" pressure, the first stage provides 25" pressure and the second stage provides 15" pressure.

The invention will now be described with reference to the drawings, of which:

Fig. 1 is a graph showing the characteristics of a two stage propeller fan embodying this invention;

Fig. 2 is a transverse section through the propeller fan, the characteristic curves of which are illustrated by Fig. 1;

Fig. 3 is a transverse section through another two stage propeller fan embodying this invention;

Fig. 4 is a transverse section through still another two stage propeller fan embodying this invention;

Fig. 5 is a plan view looking downwardly upon the propeller wheel of the first stage of Fig. 4, and

Fig. 6 is a plan view looking downwardly upon the propeller wheel of the second stage of Fig. 4.

The propeller wheels A and B of a two stage propeller fan were designed to have the characteristic curves of Fig. 1. The "burble" or stalling point of the wheel A, is shown on its characteristic curve by the dip in the curve at C. The stalling point of the wheel B is shown on its characteristic curve by the dip in the curve at D.

Propeller fans of this type are operated normally to provide pressures and corresponding volumes which occur, with respect to Fig. 1, to the

right of the dips in the characteristic curves. Thus in normal operation, no flow separation takes place. But for some duties it is necessary at times to so operate the fans as to cause the operating points to pass through the dips in the characteristic curves. When the points pass through the down slopes of these dips, troublesome pulsations are set up caused, it is believed, by the fact that negative damping occurs at points along the down slopes of the dips. For some reason not understood, there is a tendency for a fan connected to a load, to pulse. This tendency is opposed by positive damping where the pressure decreases with increase in volume and is aggravated by negative damping where the pressure increases with increase in volume. When the pressure increases with an increase in volume caused by a small pulsation in itself not objectionable, the increase in the pressure causes a further increase in volume. The effect is cumulative and troublesome pulsations are set up.

Experience has shown that where the characteristic curves have flat horizontal portions, the fans are stable when throttled through the flat portions—no observable pulsations being set up. There is no damping either positive or negative and the resistance of the system prevents pulsations.

The two wheels A and B are so designed, that their overall characteristic curve, the upper curve of Fig. 1, has no appreciable dips or peaks so that the two wheels working together operate without pulsations or surges to provide smooth performance. This is accomplished by designing the wheels so that where the characteristic curve of one wheel has a dip as at the points C or D of Fig. 1, the characteristic curve of the other wheel has a rising, compensating characteristic.

The propeller fan illustrated by Figs. 2-6 illustrate several different ways in which the first stage of a two stage propeller fan may be designed to handle substantially 60% of the work and in which the second stage may be designed to handle substantially 40% of the work. In each of the illustrated embodiments the first stage wheel and the second stage wheel differ in their blade areas. Except for this difference the blades may have the same design characteristics.

Referring now to Fig. 2, the two stage propeller fan there illustrated consists of the casing 5, the first stage propeller wheel A, the second stage propeller wheel B, the spin neutralizing vanes 6 between the wheels, the down stream spin neutralizing vanes 7 and the diffuser 8. In the embodiment illustrated, the wheel A may have 21

blades and the wheel B may have 23 blades. The vanes 6 may be 30 in number and the vanes 7 may be 27 in number.

The blades of the two wheels preferably are designed as described in my copending application, Serial No. 357,767, filed September 21, 1940, and the vanes 6 and 7 preferably are designed as described in my copending application entitled "Spin neutralizing vanes," Serial No. 365,595, now Patent No. 2,308,685.

In the embodiment illustrated by Fig. 2, the total effective surface area of the blades of the wheel A is preferably about 60% of the total effective blade area while the effective surface area of the blades of the wheel B is about 40% of the total area. The difference in the blade area of the two wheels results from the difference in the number of blades and in the difference in blade lengths of the wheels. Wheel B has a hub 9 which is larger than the hub 10 of the wheel A so that the blades of wheel A provide most of the total blade area due both to their greater number and to their greater length.

In the embodiment of the invention illustrated by Fig. 3, the hubs 9 and 10 have the same diameter and the reduction in the length of the blades of the wheel B is obtained through converging the casing 5 to form an air passage in the vicinity of and to the rear of the wheel B, which is smaller than the air passage containing the wheel A. The reduction in the blade area of the wheel B may be obtained wholly through reducing the length of the blades thereof or through the reduction in the length of the blades of the wheel B, and their number.

In the embodiment of the invention illustrated by Figs. 4, 5 and 6, the blades of wheels A and B have the same length, the reduced blade area of the blades of the wheel B being obtained by a reduction in the number of its blades. Thus as illustrated by Fig. 5, the wheel A may have 12 blades, and as illustrated by Fig. 6, the wheel B may have 8 blades. The design characteristics of all blades thus may be the same so that the wheel A has 60% of the total blade area and so that the wheel B has 40% of the total blade area, through proportioning the number of blades. The wheels A and B of Figs. 4-6 have been illustrated as having relatively small number of blades for ease of illustration. The characteristics of these wheels follow substantially, however, the curves shown by Fig. 1.

While the invention has been designed as embodied in a two stage propeller fan, it could be embodied in any multi-stage propeller fan and the principle involved of adding individual characteristics to secure a combined desired characteristic may be secured by adding two characteristics as described herein or any number more than two. In the claims, the term "multi-stage" may refer to a two stage fan or to two stages of a fan having three or more stages.

While embodiments of the invention have been disclosed for the purpose of illustration, it should be understood that the invention is not limited to the precise disclosure as other embodiments of the invention may be suggested by those skilled in the art without departure from the essence of the invention.

What is claimed is:

1. A multi-stage propeller fan with dissimilar propeller wheels, said wheels having different stalling points and being so constructed and arranged that their pressure-volume characteristic curves are such that depression in the curve

of one wheel at one pressure and corresponding volume, resulting from the stalling point of that wheel, is compensated by a rise in the curve of another wheel at the said pressure and volume.

5 2. A multi-stage propeller fan with dissimilar propeller wheels, said wheels being so constructed and arranged that they have stalling points at substantially different pressures, the pressure-volume characteristics of two of the wheels being such that the pressure from one wheel rises sufficiently at the stalling point of the other wheel to compensate for the fall in pressure at the said stalling point of said other wheel.

15 3. A multi-stage propeller fan having two dissimilar propeller wheels, said wheels being so constructed and arranged that they provide substantially different pressures at the designed volume, and that they have stalling points at substantially different pressures with such pressure-volume characteristics that the pressure from one wheel rises sufficiently at the stalling point of the other wheel to compensate for the fall in pressure at the said stalling point of said other wheel.

20 4. A multi-stage propeller fan having two dissimilar propeller wheels, said wheels having substantially different blade areas whereby one wheel provides a substantially greater pressure at the designed volume than the other wheel, said wheels being so constructed and arranged that they have stalling points at substantially different pressures with such pressure-volume characteristics that the pressure from one wheel rises sufficiently at the stalling point of the other wheel to compensate for the fall in pressure at the said stalling point of said other wheel.

25 5. A multi-stage propeller fan having two dissimilar propeller wheels, the blades of one of said wheels being substantially longer than the blades of the other of said wheels whereby one wheel provides a substantially greater pressure at the designed volume than the other wheel, said wheels being so constructed and arranged that they have stalling points at substantially different pressures with such pressure-volume characteristics that the pressure from one wheel rises sufficiently at the stalling point of the other wheel to compensate for the fall in pressure at the said stalling point of said other wheel.

30 6. A multi-stage propeller fan having two dissimilar propeller wheels, the blades of one of said wheels being substantially greater in number than the blades of the other of said wheels whereby one wheel provides a substantially greater pressure at the designed volume than the other wheel, said wheels being so constructed and arranged that they have stalling points at substantially different pressures with such pressure-volume characteristics that the pressure from one wheel rises sufficiently at the stalling point of the other wheel to compensate for the fall in pressure at the said stalling point of said other wheel.

35 7. A multi-stage propeller fan having two dissimilar propeller wheels, the blades of one of said wheels being greater in number and longer than the blades of the other of said wheels whereby one wheel provides a substantially greater pressure at the designed volume than the other wheel, said wheels being so constructed and arranged that they have stalling points at substantially different pressures with such pressure-volume characteristics that the pressure from one wheel rises sufficiently at the stalling point of said other wheel.

40 8. A multi-stage propeller fan having two dissimilar propeller wheels, the blades of one of said wheels being greater in number and longer than the blades of the other of said wheels whereby one wheel provides a substantially greater pressure at the designed volume than the other wheel, said wheels being so constructed and arranged that they have stalling points at substantially different pressures with such pressure-volume characteristics that the pressure from one wheel rises sufficiently at the stalling point of said other wheel.

point of the other wheel to compensate for the fall in pressure at the said stalling point of said other wheel.

8. A multi-stage propeller fan having one or more pairs of dissimilar propeller wheels, said wheels being so constructed and arranged that one wheel of each pair provides substantially $\frac{3}{2}$ the pressure provided by the other wheel of

said pair at the designed volume, and that the two wheels have stalling points at substantially different pressures with such pressure-volume characteristics that the pressure from one wheel rises sufficiently at the stalling point of the other wheel to compensate for the fall in pressure at the said stalling point of said other wheel.

HAROLD F. HAGEN.
